UNITED STATES PATENT OFFICE.

FRANK A. BARNEY, OF SAGINAW, MICHIGAN.

DISH-WASHING MACHINE.

1,126,347.

Specification of Letters Patent. Patented Jan. 26, 1915.

Application filed September 10, 1913. Serial No. 789,110.

To all whom it may concern:

Be it known that I, FRANK A. BARNEY, a citizen of the United States, residing at Saginaw, Michigan, have invented certain new and useful Improvements in Dish-Washing Machines, of which the following is a specification.

This invention relates to improvements in dish washing machines.

10 The main object of this invention is to provide an improved dish-washing machine which is efficient and one which is at the same time simple in structure and easy and convenient to operate.

15 Further objects, and objects relating to structural details, will definitely appear from the detailed description to follow.

I accomplish the objects of my invention by the devices and means described in the 20 following specification.

The invention is clearly defined and pointed out in the claims.

A structure which is a preferred embodiment of my invention is clearly illustrated 25 in the accompanying drawing forming a part of this specification, in which:

Figure I is a side elevation of a structure embodying the features of my invention, the plunger being shown in a raised position by dotted lines. Fig. II is a front elevation, the foot power mechanism being omitted. Fig. III is a detail vertical section on a line corresponding to line 3—3 of Fig. II, with the plunger partially elevated.

30 Fig. IV is a detail view partially in vertical section showing structural details. Fig. V is a detail horizontal section on line 5—5 of Fig. IV. Fig. VI is a detail horizontal section on line 6—6 of Fig. IV. Fig. VII is

40 a plan view. Fig. VIII is a horizontal section on a line corresponding to line 8—8 of Fig. III. Fig. IX is a horizontal section on a line corresponding to line 9—9 of Fig. III. Fig. X is a horizontal section through

45 the plunger well, on a line corresponding to line 10—10 of Fig. III. Fig. XI is an enlarged detail on a line corresponding to the curved line 11—11 of Fig. VIII, showing the means for adjustably supporting

50 the cylinder. Fig. XII is a horizontal section through the stand, on a line corresponding to line 12—12 of Fig. I. Fig. XIII is a perspective view of a basket which may be conveniently used for holding the dishes in my machine.

In the drawing similar reference charac-

ters refer to similar parts throughout the several views, and the sectional views are taken looking in the direction of the little arrows at the ends of the section lines.

Referring to the drawing, the receptacle or pan 1 is provided with a plunger well extension 2 in its bottom. The plunger well is preferably arranged at one side of the receptacle, as shown. The walls of the receptacle 1 are preferably cylindrical, and the lower portion tapered downwardly at 3. The object of this will be pointed out.

Supported within the receptacle above the plunger well 2, is a cylinder 4 having an outwardly projecting flange 5 at its upper edge and an outwardly projecting flange 6 at its lower edge. The cylinder 4 is supported in a spaced relation to the bottom of the receptacle to provide a slot-like discharge opening 7 for the water ejected from the well 2 by the plunger 8 when it is forced downward into the well. This discharge opening preferably extends entirely around the plunger as shown. The water ejected from the well by the plunger is delivered across the bottom of the receptacle and dashed against the dishes in the receptacle and against the inclined portion 3 of the wall, which deflects it upwardly and against the side and top of the receptacle where it is dashed back upon the dishes in the receptacle. The flange 6 serves to direct the water across the bottom of the receptacle.

The partition 9 is provided with a curved seat portion 10 for the cylinder. The band 11 embraces the front of the cylinder and coacts with the partition in supporting the cylinder for vertical adjustment.

The cylinder adjusting and supporting screws 12 are carried by the top flange 5 of the cylinder and engage suitable nuts 13 mounted on the top wall of the partition. See Figs. IV and XI. The nuts are rotatably secured to the flange 5, as shown in Fig. XI. By adjusting these screws, the size of the discharge opening may be regulated to secure the most effective results. If it is desired to operate the plunger slowly, the discharge opening should be quite small and when operated more rapidly, it may be quite large, it being desirable that the water should be ejected with considerable force, dashing against the dishes arranged in the receptacle and also up the inclined sides of the receptacle and

falling back upon the dishes. When the plunger is raised, the water quickly returns to the well. The plunger is made of light sheet metal and is water tight so that the water will return it to its initial or elevated position.

The guard wires 14 are arranged through the flanges of the receptacle outside of the supporting band 11 and extend into the well. The bottom of the well is provided with a supporting ring 15 for the lower ends of the wires. These guard wires prevent dishes or other articles projecting through the opening 7 below the cylinder in which position they would be engaged by the plunger and the articles broken or the plunger rendered inoperative. The wires being arranged through the plunger flanges in this way are effectively supported and at the same time, they do not in any way interfere with the adjustment of the cylinder.

The receptacle is provided with a top wall 16 through which the plunger extends, a gasket 17 being provided for the plunger. The cover 18 embraces substantially the whole of the receptacle in front of the plunger. See Fig. VII. This permits the articles to be washed being conveniently placed in or removed from the receptacle.

I preferably provide a stand consisting of suitable legs 19 with a ring-like top member 20 adapted to receive the receptacle. See Figs. I, II and XII.

The water is drawn from the well 2 which has a faucet 21, there being a channel 22 in the bottom of the well leading to the faucet.

For convenience in supporting the dishes in position for most effective work, I provide a plurality of springs 23 which have hooks at their ends 24 adapted to be engaged with lugs 25 on the bottom and side walls of the receptacle. The dishes, knives, forks, spoons, and the like can be readily engaged with these supporting springs and are effectively supported thereby and at the same time, the supports do not prevent the water reaching all parts of the articles supported thereby. If desired, the basket 26 may be used, which is of convenience in removing the dishes from the receptacle. The wires of which the basket is formed also constitute means for holding the dishes in their upright position, the wires being arranged transversely so that plates and the like supported thereby may be arranged to face the discharge orifice 7.

The plunger is provided with a hand piece 27 which may be grasped at each side of the plunger.

To adapt the structure for operation by means of the foot I provide a treadle 28 which is pivoted at 29 to one of the legs of the stand and connected by links 30 to the

hand piece 27. By this means water can be discharged with force against the dishes.

My improved washing machine is very efficient and is simple and easy to operate, and is of considerable capacity, as, owing to the shape of the receptacle, a quantity of dishes may be stacked or arranged therein. Only a small quantity of water is required to effectively wash a considerable quantity of dishes, and the dishes may be effectively rinsed merely by drawing off the washing water and introducing the rinsing water.

I have illustrated and described my improvements in detail in a simple embodiment. While I am aware that various modifications are possible without departing from my invention, I have not attempted to illustrate or describe such modifications as I believe the disclosure made will enable those skilled in the art to which my invention relates to embody the same as conditions may require. I desire, however, to be understood as claiming my improvements specifically in the form illustrated as well as broadly within the scope of the appended claims.

Having thus described my invention, what I claim as new and desire to secure by Letters Patent is:

1. In a washing machine, the combination of a receptacle, the bottom of the receptacle being provided with a plunger well disposed toward one side of the receptacle; a partition for said receptacle, said partition being provided with a cylinder seat; a sleeve-like cylinder having outwardly projecting flanges at the top and bottom thereof arranged in said seat and adjustable vertically therein, there being a supporting band on said partition embracing the front side of said cylinder whereby it is supported for vertical adjustment, the bottom flange of said cylinder being supported in a spaced relation to the bottom of said receptacle to provide a slot-like discharge opening; adjusting screws carried by the top flange of said cylinder engaging the top wall of said partition; a plunger arranged in said cylinder to reciprocate into said plunger well; and guard rods arranged through said flanges of said cylinder and projecting into said plunger well, there being a support for the lower ends of said rods in the bottom of said well.

2. In a washing machine, the combination of a receptacle, the bottom of the receptacle being provided with a plunger well disposed toward one side of the receptacle; a partition for said receptacle, said partition being provided with a cylinder seat; a sleeve-like cylinder having outwardly projecting flanges at the top and bottom thereof arranged in said seat and adjustable vertically therein, there being a supporting band on said partition embracing the front

side of said cylinder, the bottom flange of said cylinder being supported in a spaced relation to the bottom of said receptacle to provide a slot-like discharge opening; a 5 plunger arranged in said cylinder to reciprocate into said plunger well; and guard rods arranged through said flanges of said cylinder and projecting into said plunger well, there being a support for the lower 10 ends of said rods in the bottom of said well.

3. In a washing machine, the combination of a receptacle, the bottom of the receptacle being provided with a plunger well disposed toward one side of the receptacle; a partition 15 for said receptacle, said partition being provided with a cylinder seat; a sleeve-like cylinder arranged in said seat and adjustable vertically therein, there being a supporting band on said partition embracing 20 the front side of said cylinder whereby it is supported for vertical adjustment, the bottom of said cylinder being supported in a spaced relation to the bottom of said receptacle to provide a slot-like discharge 25 opening; adjusting screws carried by the top flange of said cylinder engaging the top wall of said partition; and a plunger arranged in said cylinder to reciprocate into said plunger well.

4. In a washing machine, the combination of a receptacle, the bottom of the receptacle being provided with a plunger well; a cylinder having an outwardly projecting flange at the bottom thereof, supported for vertical 35 adjustment above said well, the bottom flange of said cylinder being supported in a spaced relation to the bottom of said receptacle to provide a slot-like discharge opening; and a plunger arranged in said cylinder 40 to reciprocate into said plunger well.

5. In a washing machine, the combination of a receptacle, the bottom of the receptacle being provided with a plunger well; a cylinder supported for vertical adjustment above 45 said well, the bottom of said cylinder being

supported in a spaced relation to the bottom of said receptacle to provide a slot-like discharge opening; and a plunger arranged in said cylinder to reciprocate into said plunger well.

50

6. In a washing machine, the combination of the receptacle, a plunger well opening at its upper end into the bottom of said receptacle near one side thereof, a partition in said receptacle provided with a cylinder seat, a 55 sleeve-like cylinder mounted in said seat and vertically adjustable therein, an outwardly projecting flange on the bottom of said cylinder and spaced apart from the top edge of the plunger well whereby a slot-like discharge opening is provided between said flange and the top edge of said plunger well, a plunger slidably mounted in said cylinder and adapted to reciprocate in said plunger well, and means for reciprocating said plunger, 60 all coacting substantially as described for the purpose specified.

7. In a washing machine, the combination of a receptacle provided with a plunger well, a cylinder carried by said receptacle 70 and provided at its lower end with a flange directed laterally in a plane parallel to and slightly above the bottom of said receptacle, a plunger mounted in said cylinder and adapted to reciprocate in said plunger well, 75 and means for reciprocating said plunger whereby the water is forced out of said plunger well and directed laterally across the bottom of said receptacle by means of the flange at the lower end of said cylinder, 80 all coacting substantially as described for the purpose specified.

In witness whereof, I have hereunto set my hand and seal in the presence of two witnesses,

FRANK A. BARNEY. [L.S.]
